EMERGENCY OXYGEN GENERATOR HOUSING OR THE LIKE

Vladimir Hwoschinsky, Buffalo, N.Y., assignor to Automatic Sprinkler Corporation of America, Cleveland, Ohio

Filed Jan. 14, 1969, Ser. No. 15,331

Term of patent 14 years

Int. Cl. D23—04

U.S. Cl. D23—151

FIG. 1

FIG. 2

FIG. 3

FIG. 4

FIG. 5

FIG. 1 is a side elevational view of a housing, showing my new design;

FIG. 2 is a bottom plan view thereof;

FIG. 3 is a top plan view thereof;

FIG. 4 is a front elevational view thereof; and

FIG. 5 is a rear elevational view thereof.

The side not shown in FIG. 1 is identical to the side elevational view shown therein.

I claim:

The ornamental design for an emergency oxygen generator housing or the like, substantially as shown and described.
